UNITED STATES PATENT OFFICE.

EDWARD A. JOHNSTON, OF CHICAGO, ILLINOIS.

HORSE HAY-RAKE.

SPECIFICATION forming part of Letters Patent No. 665,226, dated January 1, 1901.

Application filed October 17, 1900. Serial No. 33,331. (No model.)

To all whom it may concern:

Be it known that I, EDWARD A. JOHNSTON, a citizen of the United States, residing at Chicago, county of Cook, State of Illinois, have 5 invented certain new and useful Improvements in Horse Hay-Rakes; and I do hereby declare the following to be a full, clear, and exact description of the invention, such as will enable others skilled in the art to which 10 it appertains to make and use the same.

The invention relates to the construction of the head of the rake and the manner of securing the teeth in place; and the particular objects in view are to economize in the amount 15 of material and the cost of manufacturing the head and to dispense with the use of bolts, nuts, and other fastenings for securing the teeth to the head.

The invention will be readily understood 20 from the following description, taken in connection with the accompanying drawing, forming part of this specification, wherein a fragment of the head of an ordinary horse-rake is shown in perspective with one of the 25 teeth in place.

Referring to the drawing, A is an angle-iron having the horizontal flange a and the vertical flange a'. This iron constitutes the head of the rake and is intended to be provided at opposite ends with axles for the supporting-wheels. Secured at appropriate intervals along this head are the teeth B, which, except at their upper ends and in the manner of securing them to the head, may be of 30 any preferred form and construction. With a view to making these teeth self-securings, and thereby to dispense with the use of the bolts, nuts, or other fastenings which have heretofore usually been employed, the horizontal flange of the head is provided near its front 35 edge with slots or holes b and the vertical flange has corresponding slots or holes b' near its lower edge.

The teeth, which are preferably constructed 40 of wire, are wound at their upper ends into a coil c, and the extremity of the wire projects upward from one side of this coil, as at c', while the main portion of the wire, forming the teeth proper, projects horizontally 45 toward the rear, as shown at d, and passes through the vertical slot b' in the flange a'. The upper end of the portion c' of the wire

projects into the slot b in the horizontal flange of the head, and the resilience of the coil pressing the end c' against the front part of 55 the slot b and the part d against the lower end of the slot b' holds the teeth firmly and securely in place.

As will be understood from the drawing, the vertical flange a' depends from the rear 60 edge of the rake-head, and the upstanding end c' of the wire being on the front side of the coil and the horizontal part d being on the lower side of the coil—the coil itself is 65 inclosed, housed, and protected in and by the angular space between the flanges. Thus the reaction of the coil causes the two portions of the wire to press in the planes of the respective flanges of the head—that is to say, in planes at right angles to each other, the one 70 horizontal and the other vertical—and the teeth are secured and held in place entirely by their own resilience, all separate fastenings being dispensed with.

The perforations b b' are herein shown as 75 elongated slots. It is not essential, however, that they should be anything more than holes; but in order to allow the body portions of the teeth the proper range of movement it is deemed specially advisable to elongate the 80 holes b', and thus allow for the desired vertical movement of the wire forming the shank of the teeth. The construction being as thus described, it is to be noted that the upper end of the tooth has four bearing-points on 85 the head—viz., in the slots b and b', against which the portions c' and d react, and at two intermediate points on the inner sides of the angular space inclosing the heads, all of which will be readily understood when it is 90 considered that the reaction of the end c' presses the rear side of the coil against the front face of the flange a' and the reaction of the part d presses the upper side of the coil against the under surface of the horizontal flange. 95

Having thus described my invention, what I claim and desire to secure is—

1. The combination with a rake-head formed of angle-iron, of a wire tooth having a coil at 100 its upper end, the extremity of the wire on one side of the coil engaging the horizontal flange of the head, and the wire on the opposite side of the coil passing through the ver-

tical flange of the head, the tooth being held to the head by the resilience of the wire reacting between its flanges in planes at right angles to each other.

5 2. The combination with a rake-head formed of angle-iron, of a wire tooth having a coil at its upper end, the extremity of the wire on one side of the coil engaging a slot or perforation in the horizontal flange of the head, and the portion of the wire on the opposite side of the coil passing through a slot or perforation in the vertical flange of the head, the tooth being held to the head by the resilience of the wire reacting in the planes of the flanges.

15 3. The combination with a rake-head formed of angle-iron having horizontal and vertical flanges, of a wire tooth having a coil at its upper end inclosed within the flanges, the wire on the opposite sides of the coil engag-

ing slots or perforations in the respective flanges, and the resilience of the wire reacting in the planes of the flanges to hold the tooth to the head.

4. The combination with a rake-head formed of angle-iron having vertical and horizontal flanges, of a wire tooth having its upper end passed through a slot or perforation near the lower edge of the vertical flange and wound into a coil inclosed in the angle between the flanges and having its extremity extended upward through a slot or perforation in the horizontal flange.

In testimony whereof I affix my signature in presence of two witnesses.

EDWARD A. JOHNSTON.
